CLAIM

The ornamental design for an elastic band for warming the hand of a user, as shown and described.

DESCRIPTION

FIG. 1 is a front elevation view of an elastic band for warming the hand of a user showing concave edges; FIG. 2 is a rear elevation view of the elastic band; and, FIG. 3 is a view of the elastic band placed around the hand of a user, with the concave edges adjacent the palm of the hand.

The broken line showing of the hand of the user in FIG. 3 is for the purpose of illustrating environmental structure and forms no part of the claimed design.
